UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

REVERSIBLE BRUSH-HOLDER FOR USE WITH DYNAMOS.

1,253,157.

Specification of Letters Patent.

Patented Jan. 8, 1918.

Application filed August 7, 1911. Serial No. 642,582.

To all whom it may concern:

Be it known that I, JOHN L. CREVELING, a resident of New York, in the county and State of New York, have invented certain new and useful Improvements in Reversible Brush-Holders for Use with Dynamos, as set forth in the annexed specification and drawing forming a part thereof.

My invention pertains to that class of 10 dynamos wherein it is desired to maintain the current of uniform polarity regardless of reversals in direction of rotation of the armature, and has for its particular object to provide means for satisfactorily compensating for reversals in rotation of the armature.

The drawing is a partial section and elevation of a portion of a dynamo comprehending my invention.

In the drawing, 1 represents the usual 20 armature of a dynamo provided with the commutator 2, the said armature being carried by the usual shaft (not shown) running in the usual type of bearing carried within the bearing member, or casting, 3 which is preferably provided with a flanged portion 4 adapted to be held firmly against the end of the field frame indicated at 5 as by screws 6. The bearing member or end casting also carries a cylindrical extension 30 7 provided with a ball-race or channel indicated at 8 into which are free to travel the balls 9 engaging a corresponding ball-race in an annular ring 10 which is provided with arms 11 carrying suitable brush-

holders as indicated at 12 which are provided with brushes as indicated at 13. As the ball bearing for the ring 10 will allow the said ring to rotate with very little friction, the drag or friction of the brushes 13 upon the commutator 2 will rotate the ring 10 in one direction or the other depending upon the direction of rotation of the armature unless stopped by some engaging means. For this purpose I provide a stop 14 which 40 will allow the ring 10 and brushes 13 to revolve through substantially one hundred and eighty degrees when a bi-polar machine, as indicated in the drawing, is used. This revolution of the brushes in one direction or 50 the other will shift the brushes from one end of the axis of commutation to the other and, therefore, cause the brush which is the positive brush when the generator is running in one direction to occupy the position of the negative brush when running in

the other direction, and thus compensate for changes in direction of the armature current in a well-known manner. I have shown a bi-polar machine for sake of simplicity and it will be obvious that a machine with any 60 proper number of poles may be used and the arc through which the brushes are shifted determined accordingly to accomplish the result outlined above. In order to more securely hold the ring 10 in its proper position when the generator is in operation and to prevent chattering of the brushes from tending in time to wear or pit the ball-races, I provide an annular electromagnet, the field frame of which is indicated at 15 and 65 which may be carried as upon brackets of brass, or other non-magnetic material, indicated at 16. A series of small spiral springs 17 are preferably let into recesses in the member 7 and tend to press the magnet 70 away from the ring 10 and the face of the member 7, the brackets 16 being so adjusted that the air gap between the magnet frame 15 and the members 10 and 7 is very 75 small always. The magnet is provided with the winding 18 dependent for excitation upon the armature 1 as, for example, placed in shunt across the generator brushes as indicated in the drawing. 19 represents one of a series of slip pins which may be used 80 if desired to keep the magnet frame 15 from revolving upon its brackets or support.

The operation of my dynamo is substantially as follows:

If the armature 1 and commutator 2 be 90 revolving in such direction that the top portion of the armature is moving toward the observer, then the friction of the brushes will cause the arm 11 to revolve the member 10 until arrested by the stop 14 and the 95 parts will be in the positions shown in the drawing. If now the generator speed increase until its voltage be appreciable, the winding 18 will become energized and the magnet frame 15 will be drawn into contact 100 with the face of the member 7 and the ring 10, to which members it is preferably smoothly fitted. As this will form an exceptionally good magnetic circuit the tractive effect of the electromagnet will be considerable, and the ring 10 will be rigidly held in its proper position and practically no strain will be borne by the balls 9 and ball-race 8. The ring 10 will be firmly held by the magnet 15—18 so long as the generator elec- 105 110

tro-motive force be appreciable or sufficient to be useful. If, however, the generator speed be brought down to *nil*, its electro-motive force will fall to zero, and the springs 5 will press the annular magnet away from the members 7 and 10, and the brushes will be free to revolve into the reverse position. If the generator armature now be revolved in a reverse direction the revolving of the brushes will maintain the current of proper 10 polarity to line and the magnet 15-18 will again become energized and grasp the members 7 and 10 and hold the ring 10 firmly in place and relieve the balls and ball-races 15 of strain as above outlined.

From the foregoing it will be obvious that my dynamo is provided with a pole changing apparatus and electromagnetic means for carrying the mechanical strain usually 20 borne by the pole changer bearing when the generator is running and that when the generator is still and in condition for reversal the pole changing apparatus will be released and capable of proper action upon said 25 reversal.

I do not wish in any way to limit myself to any details of construction or exact mode of operation set forth in this specification, which are given to illustrate one type of 30 generator embodying the essentials of my invention, for it will be obvious to those skilled in the art that wide departure in the

way of details may be made without departing from the spirit and scope of my invention which is as set forth in the following claims:

1. A dynamo electric machine having an armature and a commutator; together with a plurality of commutator brushes, and brush-holding devices adapted to be moved by friction of the brushes with the commutator in either direction through definite arcs; means for pivotally connecting the brush-holding devices with a stationary part 40 of the machine, and stationary means connected with a stationary part of the machine for limiting the movement of said brush-holding devices; in combination with magnetic means for retaining the brush-holding 45 devices at their limit of movement.

2. A dynamo electric machine having an armature, a commutator, and brush-holding devices; means for pivotally supporting said devices permitting motion thereof in either 50 of two directions; a stationary means for limiting the movement of said brush-holding devices in either direction; and magnetic means for securely holding said devices in accordance with the direction of rotation of 55 the armature.

JOHN L. CREVELING.
